UNITED STATES PATENT OFFICE

2,276,021

METHOD OF AND APPARATUS FOR DETERMINING BLEEDING TIME

Alfred L. Copley, Kansas City, Kans., and Joseph J. Lalich, Kansas City, Mo.

Application April 24, 1941, Serial No. 390,142

7 Claims. (Cl. 128—2)

This invention relates to improvements in the method of and apparatus for determining bleeding time and has for its principal object the method and means for determining the bleeding time of a human while the wound is immersed in a solution which is maintained at a substantially uniform, pre-determined temperature.

A further object of the present invention is the provision of the method and means for measuring the bleeding time of a human while the wound is immersed in an illuminated solution maintained at a substantially constant temperature.

Another object of this invention is the provision of an apparatus comprising an efficient and adjustable means whereby the bleeding time of a human may be observed while the wound is immersed in an illuminated solution which is maintained at substantially a pre-determined uniform temperature.

Other objects are simplicity and economy of construction, ease and accuracy of operation and adaptability for use with any portion of the human body during a bleeding operation.

With these as well as other objects which will appear during the course of the specification, in view, reference will now be had to the drawing wherein.

Figure 1 is an elevational view, partly broken away, of an apparatus for determining bleeding time, embodying the invention.

Fig. 2 is a plan view of the apparatus; and

Fig. 3 is a diagrammatic view of the electric circuit.

Referring now to the drawing wherein like reference characters refer to similar parts the numeral 10 designates a base member preferably made of an electric insulating material and a material that will resist relatively high temperatures. A vertically disposed opening 12 extends through base 10 and is provided adjacent its top with inwardly disposed projections 14 which serve to support a transparent beaker or container 16 in which is deposited a suitable solution 18.

A heater 20 is positioned in base 10 directly beneath container 16. The heater shown is an electric heater of the commercial type having a resistance coil 22, and is made of annular form so as to provide an opening 24 through which light from lamp 26 is directed through the bottom of container 16 to illuminate the solution 18 contained therein. The reflector 28 carried by

the closure 30 for opening 12 reflects the lamp light to the solution.

Extending upwardly from base 10 is a body member support 32 having a section 34 hinged at 36 for movement to and from a position in said container. A human hand H is shown in the operative position on support 32 for a bleeding operation. To support other body members for bleeding tests it is apparent that the shape and size of the apparatus will necessarily be altered to accommodate the particular part.

A thermo electric switch 38 which opens when a predetermined temperature is reached, is mounted in the hinged support section 34 and is adapted to be immersed in the solution being heated. A suitable thermometer 40 carried by section 34 will indicate the temperature of the solution during the bleeding operation.

A recess 42 is formed in base 10 to receive the light bulb 44 which when lighted directs light rays through window 46.

Reference will now be had to the diagrammatic view shown in Fig. 3 wherein 48 and 50 designate electric supply line wires. One end of the heating coil 22 is connected to line wire 50 through wire 52 having a switch 54 and the other end thereof is connected to one terminal of temperature controlled switch 38 through wire 56 having a lamp 44 in series therewith. The other terminal of switch 38 is connected by wire 58 to line wire 48.

The solution illuminating lamp 26 is connected by wire 60 to wire 58 and by wire 62 to wire 52 so that as long as switch 54 is closed it will be illuminated.

The thermo electric switch 38 is of the type which may be opened when a pre-determined temperature of the solution in which it is immersed, is reached. Such a switch is clearly disclosed in U. S. Patent No. 2,090,407.

The solution 18 normally used in the bleeding test is an isotonic solution in which the proper amount of sodium chloride is present to keep the blood in its substantially normal physiological condition. Hypotonic or hypertonic solutions might also be used, furthermore other substances might be used to shorten or prolong the bleeding time or to meet certain requirements which may appear under abnormal conditions.

In the use of this method and apparatus it is convenient to show an apparatus suitable for use when the bleeding is from the human finger.

The apparatus is placed at rest on a support so that the severed capillaries of the finger at the wound W will be substantially in hori-

zontal alignment with the patient's heart so as to eliminate venous hemodynamic pressure. If it becomes necessary to make the bleeding test with the wound and heart out of horizontal alignment then the gravity corrections can be made by simple calculations.

The bleeding test may be carried out in the following manner. The container is substantially filled with an isotonic saline solution and positioned in the operative position in base 10. Switch 54 is closed to light lamps 26 and 44 and to furnish current to heater coil 22. When the temperature of the solution has reached the predetermined temperature, preferably the normal human body temperature, then the thermo controlled switch 38 will operate to cut off the current to lamp 44 and heater coil 22. Should the temperature of the solution drop an objectional amount the switch 38 will automatically operate to close the circuit to again light lamp 44 and energize the coil 22. The finger is cleaned with alcohol and immersed in the warmed solution for a few minutes until it is of substantially the same temperature as the solution. The finger is temporarily removed from the solution and the blood capillaries are severed by lancing or by cutting away a portion of the skin. The finger is now immersed in the warm solution. The blood B, due to its specific gravity, will normally move downwardly to the bottom of the container and due to its color will be readily visible through the illuminated saline solution.

The operator can take an accurate reading of the time period that ellapses between the severing of the capillaries and the stopping of the blood flow, by means of a stop watch. When the wounds are inflicted by means of a lancet, the lancet blade of a definite size, usually 2 mm. x 6 mm., is used so as to obtain substantially the same bleeding surfaces. It is considered more accurate to sever the blood capillaries by removing a small section of the skin.

While this method and apparatus is used to determine human bleeding time, yet it is apparent that it may also be used for determining the bleeding time when the pneumatic cuff with varying pressure is employed; the effect of various fluids and solutions on the bleeding time; testing the fragility of the blood cells; and to test coagulation of the blood.

When it is desired to obtain tests from other portions of the body it is evident that this can be accomplished by making the necessary changes in the supporting and immersing both so as to conform to the particular shape of the body parts.

Having thus described the invention, what is claimed as new and desired to be secured by Letters Patent is:

1. The method of determining the bleeding time of a human comprising severing capillaries of a human body member to cause bleeding, immediately immersing said exposed capillaries in a solution maintained at substantially the temperature of said body member, then measuring the time period from the severing of said capillaries to the instant the blood flow stops as indicated in said solution.

2. The method of measuring the bleeding time of a human comprising immersing a human body member in an illuminated isotonic, saline solu-

tion maintained at substantially the temperature of said body member, severing blood capillaries of said body member to cause bleeding, then measuring the time period from the severing of said capillaries to the instant the blood flow from said severed blood capillaries stops as indicated in said solution.

3. The method of measuring the bleeding time of a human comprising immersing a human body member in an illuminated saline solution maintained at substantially the same temperature as that of said body member, severing blood vessels in said body member to cause bleeding, then measuring the duration of time from the severing of said blood capillaries to the time the blood ceases to flow therefrom.

4. The method of determining the bleeding time of a human comprising immersing a human body member in a transparent receptacle containing an isotonic saline solution maintained at substantially the human body temperature, directing a relatively strong light through said saline solution, severing blood vessels in said body member within said solution, then measuring the time period between the severing said blood vessels and the instant the blood flow from said severed blood vessels stops.

5. An apparatus for determining the bleeding time of a human comprising a base, an open top transparent container removably carried by said base, a body member support carried by said base having a hinged section adapted to be moved to and from a position in said container, heating means for heating a solution in said container, a lamp positioned below said transparent container to illuminate the solution contained therein, and means controlled by the temperature of said solution to regulate said heating means to maintain said solution at a substantially constant pre-determined temperature.

6. An apparatus for determining the bleeding time of a human comprising a base, an open top transparent container carried by said base having a movable support carried by said base having a movable section to be adjusted to and from a position above said container, heating means for heating a solution in said container, a lamp positioned in said base below said transparent container whereby light is directed upwardly through said solution, and means controlled by the temperature of said solution to regulate said heating means whereby the temperature of said solution is maintained at a substantially constant pre-determined temperature.

7. An apparatus for determining the bleeding time of a human comprising a base, an open top transparent container carried by said base, a body member support carried by said base having a movable section to be adjusted to and from a position above said container, a ring-shaped heating means for heating a solution in said container positioned below said container, a lamp positioned in said base below said heater whereby light is directed therethrough and upwardly through said solution, and means controlled by the temperature of said solution to regulate said heating means whereby the temperature of said solution is maintained at a substantially constant pre-determined temperature.
